UNITED STATES PATENT OFFICE.

WALTER BRINTON, OF HIBRIDGE, NEW JERSEY, ASSIGNOR TO TAYLOR IRON AND STEEL COMPANY, A CORPORATION OF NEW JERSEY.

BOLTING MECHANISM FOR ROTARY-DOOR SAFES OR VAULTS.

SPECIFICATION forming part of Letters Patent No. 793,345, dated June 27, 1905.

Application filed October 1, 1904. Serial No. 226,742.

To all whom it may concern:

Be it known that I, WALTER BRINTON, a citizen of the United States, residing in Highbridge, in the county of Hunterdon and State of New Jersey, have invented certain new and useful Improvements in Bolting Mechanism for Rotary-Door Safes or Vaults, of which the following is a specification.

The present improvement relates to locking or bolting mechanism particularly adapted for use with rotary-door safes and is especially organized for connection with an automatic for governing the manipulation of such bolting mechanism, the present improvement being especially designed for use in connection with that form of safe shown in my two contemporaneously pending applications, Serial Nos. 194,655 and 226,442, filed, respectively, February 23, 1904, (now Patent No. 771,704, dated October 4, 1904,) and September 29, 1904, in which a rotary door is maintained in its seat by means of locking-lugs having plane meeting or locking faces.

An object of the invention is the provision of an improved organization of mechanism in which rotatable bolts are controlled in their movements by an automatic, which in turn is controlled by lock mechanism, such as time-lock mechanism.

One of the objects of the present invention is the provision of bolting mechanism which while operated by a spindle has its retracting movement governed by an automatic.

A further object of the invention is the provision of bolting mechanism including clutch mechanism under the control of an automatic, having means for controlling the automatic until the bolts have been protracted.

Another object of the invention is the provision of an improved organization of bolting mechanism in which right and left hand threaded rotatable bolts may be used.

In the drawings accompanying and forming part of this specification, Figure 1 is an interior view of a portion of a door, showing this improved bolting mechanism. Fig. 2 is a sectional view of the door, taken on line *aa*, Fig.

3, looking toward the rear of such door. Fig. 3 is a view taken on line *bb*, Fig. 2; and Fig. 4 is a sectional perspective view showing the means provided for securing the door in its seat against both rotary movement and the withdrawal thereof, such view illustrating the particular manner in which the parts are assembled with relation to each other. 55

Similar characters of reference indicate corresponding parts in the several figures of the drawings.

The door 2 and body 3 are provided in the present instance with integral locking-lugs 4 and 4', respectively, having plane meeting or locking faces 5, whereby there is no backlash or appreciable tendency of the door to creep back in its jamb. For the purpose of locking such a door in its seat the door is provided with a pair of rotary bolts 6, having smooth circular bolt-heads 6', which may be a part of or tightly screwed on right and left hand threaded portions or shanks 7, threaded into openings 8, formed in the metal of the door, to permit which when the door is made of unmachinable metal, as is usual, inserts of soft metal or steel which can be readily threaded will be provided in a rearwardly-extending flange thereof. For rotating these bolts a bevel-gear 9, mounted on a sleeve 10, located on the square ends or splined to the ends of the bolts, is provided, so that the bolts may move longitudinally of the sleeve during the rotation thereof, and meshing with this bevel-gear is a bevel-gear 11, secured to the end of a spindle 12, which projects through the door. Since the bolts could be rotated to retract the same after they were protracted unless some means was used to prevent this, the bevel-gear 9, carried by the sleeve, is shown loosely mounted upon such sleeve, and for the purpose of fixedly connecting it with such sleeve, and thereby with the bolts, a clutch 13 is provided, the clutch-teeth 14 of one member thereof being formed on or as a part of the bevel-gear, while the other portion 15 of the clutch is splined to the sleeve and is under the control of a clutch-shifter 16, pivotally secured

to a plate 17, located in a chamber 18 of the door, which may be formed with a flange 19, so as to provide this chamber for the reception of the operating parts of the bolting mechanism. The door may also be provided with an annular shoulder 20 for the attachment of a plate 21 for the lock mechanism, which, as shown, comprises a time-lock 22 and an automatic 23, the details of which it is not necessary to show herein, they being of the usual construction. The automatic has a projecting pin or stud 24 at its rear, which extends into an opening 25 of the clutch-shifter 16, and when this automatic through the action of its springs retracts its plunger or carriage 24' in the usual manner after the time movements of the timing mechanism have run down, so as to trip the automatic, the clutch-shifter is moved so as to throw the splined 20 clutch member into engagement with the bevel-gear clutch member, thereby connecting the latter with the bolts, whereupon on the rotation of the spindle the bolts will be retracted.

25 When starting the timing mechanism, it is of course necessary to set the automatic before the door is closed, and this setting of the automatic tends to protract the plunger or carriage and set and latch the levers which hold the carriage in its protracted position. This movement of the carriage throws the splined clutch member through the medium of the clutch-shifter away from the bevel-gear, so that upon the closing of the door it would not be possible to protract the bolts, since the bevel-gear located on the sleeve would run idle. To prevent the movement of the carriage, and thereby the clutch-shifter, notwithstanding the setting of the locking-30 levers of the automatic until the bolts have been fully protracted by the spindle, I have provided means which I term an "automatic-controller" and which in the form shown comprises a spring-actuated lever 26, one end 27 of which has a pin or stud 27' engaged by a shoulder or flange 28 on one of the bolts and the other end of which is provided with an offset or hook 29 to engage a corresponding hook 30 on the clutch-shifter, such controller being 35 pivotally supported to one of the plates—as, for instance, the plate 21—which sustains the time and automatic mechanism. When the bolts are in their retracted position, the spring of the controller hooks it into the clutch-shifter, so that when the levers of the automatic are set the carriage or plunger of such automatic is prevented from moving into its protracted position. This maintains the clutch members in engagement, so that the bolts 40 may be protracted by the spindle into the jamb of the body. When the bolts have been fully protracted, the controller has been moved to release the clutch-shifter, whereupon the carriage or plunger under the ac-

tion of its springs is immediately protracted, 65 throwing the clutch through the medium of the clutch-shifter away from the bevel-gear clutch-teeth, and thus separating the clutch members, so that should the spindle be turned the bolts will not be retracted. When the 70 time-lock, as stated, runs down and trips the automatic, the carriage moves to the left, Fig. 1, and thereby shifts the splined clutch member into engagement with the clutch-teeth of the bevel-gear, so that the bolts can 75 be retracted by the spindle, after which the door may be rotated and withdrawn.

By having the bolts rotatable by means of right and left hand threads, a large number of which threads can be provided, it is believed that the bolts cannot be rotated into their protracted position by vibration, and especially is this so in view of the peculiar formation of the locking-lugs—that is to say, by having the lugs plane-faced there is not only 80 no tendency of the door to creep back, as in those structures where the lugs have tapered faces or the door is secured by a continuous thread or mutilated thread-sections, but the bolts not being under tension owing to the 85 plane faces of the lugs are not under a constant strain, so that not only can rotatable bolts be used, but there is no tendency of such bolts to retract. Furthermore, by having plane-faced lugs the locked position of the 90 door will always be the same—that is to say, the door can always be rotated to the same precise point, determined by a stop, so that the bolts can be readily rotated into their bolt-sockets, which they may fit with a high degree of precision, whereas when continuous or mutilated thread-segments or tapered lugs are used the door may be rotated either not quite so far or farther at one time than another, since wear upon the threads or lugs 95 would permit the door to be rotated into its wedged position farther at one time than another, while in other cases some persons might use more power than others to rotate the door to its seat, thus rotating it farther than others, in view of which circumstances it has heretofore been necessary to form the bolt-holes in the jamb with sufficient room to permit the bolts to be protracted by the automatic provided the door was rotated approximately to 100 its final position. In the present improvement, however, as the door may always be rotated to a certain point, no greater power being necessary to rotate it to this point at one time than at another, nor will any wear of the lugs permit it to be rotated to a different point at one time from that to which it was previously rotated, not only may threaded rotary bolts be used, but they may fit snugly 105 into the jamb, the openings in the jamb being round, and in practice they would be formed in soft metal or steel inserts, the walls of which, together with the ends of the bolts,

being so precisionized as to give this snug fit, thus preventing any movement of the door within its jamb whatsoever. The ends of the bolts may be beveled or tapered to facilitate the starting in of such bolts.

The bolts are shown in the present instance as located between the inner ends of the door-lugs 4 and the shoulder 30' of such door and project into a pair of body-lugs 4', the openings of which may be, as stated, provided with inserts which may be readily machined when the door is, as is usual, made of unmachinable metal.

The term "automatic" as used herein is intended to mean an organization of power mechanism such, for instance, as that now well known on the market and which is constructed and adapted to operate the bolts or locking devices of a safe or vault door under the control of a lock mechanism—such, for instance, as a time-lock.

Having thus described my invention, I claim—

1. A safe or vault door bolting mechanism comprising rotatable, threaded bolts located to project at the periphery of the door, and means for rotating said bolts and comprising a spindle, gearing for communicating motion from said spindle to the bolts, clutch mechanism to effect or break such connection, and time-lock mechanism and an automatic for controlling the connection of such clutch mechanism.

2. A safe or vault door bolting mechanism comprising rotatable bolts shiftable endwise beyond the periphery of the door and an automatic for controlling the rotation of said bolts through intermediate mechanism.

3. A safe or vault comprising a body and a rotary door, having integral locking lugs or surfaces provided with plane-faced meeting or locking parts, and means for preventing the rotation of the door in its seat and comprising rotary bolts.

4. A safe or vault comprising a body and a rotary door having integral locking lugs or surfaces provided with plane-faced meeting or locking parts, and means for preventing the rotation of the door in its seat and comprising rotary bolts having right and left hand threaded portions.

5. A safe or vault comprising a body and an integral rotary door having integral locking-lugs provided with plane-faced meeting or locking parts, means for preventing rotation of the door within its seat, comprising bolts projecting into the jamb thereof, provided with right and left hand threaded portions, and an automatic for controlling the retraction of said bolts.

6. A safe or vault comprising a body and a rotary door, having integral locking lugs or surfaces provided with plane-faced meeting or locking parts, means for preventing the

rotation of the door in its seat and comprising 65 rotary bolts, a spindle, means connecting said spindle with said bolts, and an automatic for governing the connection between said spindle and said bolts.

7. A safe or vault comprising a body and 70 a rotary door having integral locking lugs or surfaces provided with plane-faced meeting or locking parts, means for preventing the rotation of the door in its seat and comprising rotary bolts, and an automatic for controlling 75 the retraction of said bolts.

8. A safe or vault comprising a body and a door having coöperating integral locking-lugs, said door having an annular shoulder adapted to engage the outer ends of the body-lugs and limit inward movement of the door, and means for preventing rotation of the door, comprising bolts located to project intermediate the shoulder and lugs of the door and into the jamb of the body. 85

9. A safe or vault comprising a body and a door having coöperating integral locking-lugs, said door having an annular shoulder adapted to engage the outer ends of the body-lugs and limit inward movement of the door, 90 means for preventing rotation of the door, comprising bolts located to project intermediate the shoulder and lugs of the door and into the jamb of the body, and an automatic for controlling the retraction of said bolts. 95

10. A safe or vault door bolting mechanism comprising bolts having threaded shanks and located to project at the periphery of the door, means for actuating said bolts, and an automatic for controlling the movements of 100 said bolts.

11. A safe or vault door bolting mechanism comprising rotatable bolts having threaded portions and located to project at the periphery thereof, a spindle, means for connecting said 105 spindle with the bolts and an automatic for controlling such connection.

12. A safe or vault door bolting mechanism comprising rotatable bolts located to project at the periphery thereof, a spindle, means for connecting said spindle with the bolts and an automatic for controlling such connection. 110

13. A safe or vault door bolting mechanism comprising right and left hand threaded rotatable bolts located to project at the periphery 115 thereof, a spindle, gearing for communicating motion from said spindle to the bolts, clutch mechanism to effect or break such connection, and means for controlling the connection of such clutch mechanism. 120

14. A safe or vault door bolting mechanism comprising right and left hand threaded bolts located to project at the periphery thereof, a spindle, gearing for communicating motion from said spindle to the bolts, clutch mechanism to effect or break such connection, and an automatic for controlling the connection of such clutch mechanism. 125

15. A safe or vault door bolting mechanism comprising rotatable bolts, a spindle, a bevel-gear carried thereby, a bevel-gear in mesh therewith, clutch mechanism connecting said last-mentioned bevel-gear with the rotatable bolts, a clutch-shifter, and an automatic connected with such clutch-shifter for controlling the retraction of the bolts.
16. A safe or vault door bolting mechanism comprising rotatable bolts, a spindle, a bevel-gear carried thereby, a bevel-gear in mesh therewith, clutch mechanism connecting said last-mentioned bevel-gear with the rotatable bolts, a clutch-shifter, an automatic connected with such clutch-shifter for controlling the retraction of the bolts, and means for controlling the action of the automatic until the bolts are protracted.
17. In a safe or vault door bolting mechanism, the combination of locking-bolts, means for shifting said bolts and including a clutch-shifter, and an automatic connected with said clutch-shifter to control the movement thereof.
18. In a safe or vault door bolting mechanism, the combination of locking-bolts, an automatic for controlling the retraction of said bolts, and means for preventing movement of the carriage or plunger of said automatic during the protraction of such bolts.
19. In a safe or vault door bolting mechanism, the combination of locking-bolts, a spindle for working said bolts, and an automatic for controlling the retraction of said bolts through intermediate mechanism.
20. In a safe or vault door bolting mechanism the combination of locking-bolts, an automatic for controlling the retraction of said bolts, and means under the control of one of the bolts for preventing movement of the carriage or plunger of said automatic during the protraction of such bolts.
21. In a safe or vault door bolting mechanism, the combination of locking-bolts, a spindle for working said bolts, an automatic for controlling the retraction of said bolts, and means under the control of one of the bolts for controlling said automatic during the protraction of such bolts.
22. In a safe or vault door bolting mechanism, the combination of locking-bolts, means for shifting said bolts and including a clutch-shifter, an automatic connected with said clutch-shifter to control the movement thereof, and means for preventing the movement of said clutch-shifter during the setting of said automatic.
23. In a safe or vault door bolting mechanism, the combination of locking-bolts, means for shifting said bolts and including a clutch-shifter, an automatic connected with said clutch-shifter to control the movement thereof, and means for preventing the movement of said clutch-shifter during the setting of
- 15 20 25 30 35 40 45 50 55 60
15. A safe or vault door bolting mechanism having connection with one of the bolts and controlled by the movement thereof.
24. A safe or vault door bolting mechanism comprising rotatable bolts, an automatic controlling the retraction of said bolts, and means controlled by one of said bolts for controlling the action of said automatic during the protraction of the bolts.
25. A safe or vault door bolting mechanism comprising a plurality of right and left hand threaded rotatable bolts, a spindle, a bevel-gear carried thereby, a bevel-gear in mesh therewith, a clutch for connecting said last-mentioned bevel-gear with the bolts to permit the rotation thereof by the spindle, a clutch-shifter, an automatic connected with said clutch-shifter for controlling the action of said clutch, and a controller for said automatic to prevent the separation of the clutch members during the setting of the automatic.
26. A safe or vault door bolting mechanism comprising a plurality of right and left hand threaded rotatable bolts, a spindle, a bevel-gear carried thereby, a bevel-gear in mesh therewith, a clutch for connecting said last-mentioned bevel-gear with the bolts to permit the rotation thereof by the spindle, a clutch-shifter, an automatic connected with said clutch-shifter for controlling the action of said clutch, and a controller for said automatic to prevent the separation of the clutch members during the setting of the automatic, said controller having connection with one of the rotatable bolts so that when the same are protracted the clutch-shifter will be released to permit the separation of the clutch members by the automatic.
27. A safe or vault comprising a body and a rotary door, having integral locking lugs or surfaces provided with plane-faced meeting or locking parts, means for preventing the rotation of the door in its seat and comprising rotary bolts and lock mechanism controlling the operation of said bolts.
28. A safe or vault comprising a body and rotary door having integral locking lugs or surfaces provided with plane-faced meeting or locking parts, and means for preventing the rotation of the door in its seat and comprising bolts having right and left hand threaded portions.
29. A safe or vault door bolting mechanism comprising right and left hand thread rotatable bolts located to project at the periphery of the door, means for rotating said bolts, and an automatic for controlling the rotation of such bolts.
30. A safe or vault door bolting mechanism comprising threaded, rotatable bolts, and an automatic for controlling the rotation of said bolts through intermediate mechanism.
31. A safe or vault door bolting mechanism comprising threaded, rotatable bolts, an au-

tomatic for controlling the rotation of said bolts, and a lock mechanism for controlling the action of the automatic.

32. A safe or vault door bolting mechanism comprising rotatable bolts shiftable endwise beyond the periphery of the door an automatic for controlling the rotation of said bolts,

and means for controlling the action of the automatic.
